UNITED STATES PATENT OFFICE

GEORGES VIARD, OF PARIS, FRANCE

TELECOMMUNICATION SYSTEM

Application filed November 10, 1930, Serial No. 494,758, and in France January 8, 1930.

The present invention relates to improvements in and relating to telecommunication systems, and more particularly to an improved method of and apparatus for two-way communication over a single circuit common to both directions of transmission.

In telecommunication systems, and more particularly in long-distance signalling systems, the exchange of signals is generally effected by means of a system called the 4-wire system, and in order to establish a two-way communication between two stations A and B, two separate circuits are employed, the one used for transmission from A towards B and the other used for transmission from B towards A. The use of two separate circuits is necessary because the one-way amplifiers arranged in each of the circuits can only transmit the current in a single direction, but the exchange of signals or conversations never takes place simultaneously in the two directions and the two circuits are thus never traversed simultaneously by the communication currents.

In order to reduce the number of lines and wire necessary in the above systems, other systems have already been proposed in which the communication currents are transmitted over a single circuit common to both directions of transmission and the amplifiers of which can be controlled to transmit in turn in each direction of the communication currents. In these systems, however, when the apparatus is at rest the amplifiers are set to transmit in a predetermined direction and this has the disadvantage that the beginning of a conversation may be badly transmitted if the previous setting of the amplifiers does not correspond to the direction of transmission of the conversation.

The present invention has for object to provide a telecommunication system in which the exchange of signals is effected over a single circuit common to both directions of transmission and employing single-way amplifiers, wherein the above stated disadvantages are overcome.

According to the invention, to this end, the amplifiers or repeating means along the line are each controlled by means of a com-

municating device or the like, so that their direction of transmission is continuously reversed, at predetermined intervals of time, to set the line alternately for transmission in each direction of communication, the reversals or alternations following one another with a frequency high enough to permit of the correct transmission of a vocal emission or signal element coming from either one of the stations.

At the beginning of a transmission from one of the stations, each amplifier is then set by means of a suitable control device to transmit only in the appropriate direction for the communication, and when the latter stops, the amplifiers are controlled again to continuously reverse the direction of transmission of the line, until another communication current is sent out from one of the stations.

The reversals or alternations in the direction of transmission of the amplifiers are taken up again with only a slight delay, which is nevertheless greater than the normal pauses which occur during the course of a conversation.

Preferably, at the beginning of the communication, the reversals of the direction of transmission of the amplifiers are not stopped immediately, but continue for a certain interval of time so as not to lose the first parts of the speech during the operation of the direction-controlling means.

By way of example, a particularly suitable frequency for the reversals of the amplifiers has been found to be 500 per second. During this time, therefore, the amplifiers still transmit alternately in both directions, the frequency of the reversal being such that speech currents from either station will be transmitted and heard.

The fact that the first part of the communication currents are not lost, whilst effecting, at the same time, the setting of the amplifiers or repeaters to transmit only in the direction of the communication, is a particularly important advantage according to the invention realized over the known systems of telecommunication of this kind.

The reversal of the direction of transmis-

sion of the amplifiers may be effected in two different ways:

(a) All the amplifiers may be controlled in synchronism, in such a manner that all the sections of the circuit are controlled together to transmit alternately in each direction of communication,

(b) The reversal of the direction of transmission of the different amplifiers is not effected in synchronism, the commutating devices or the like operate independently and the reversal of the various sections is effected in turn.

In order that the invention may be more clearly understood, it is described herein-after, by way of example, with reference to the accompanying drawing in which:

Fig. 1 is a general view of an amplifying station according to the invention.

Fig. 2 is a detailed view of part of the commutating device.

With reference to Fig. 1, the two sections of the transmission line are represented at 10 and 11, 12 being the line amplifier and 14 and 15 two detector-amplifiers co-operating with two electro-magnets 16 and 17. 13 is the commutating device according to the invention in which 27 is the commutating cylinder, 22 the commutator brushes, 23 and 24 contacts connected to the line 10—11, and 25 conducting rings individually numbered 1 to 6 starting from the top. 19 is the commutator collector, 20 the collector brushes connected to the input terminals of the amplifier 12 and 21 the collector brushes connected to the output terminals of the amplifier. 18 is an electric motor for driving the commutating devices and 26 controlling devices for displacing the cylinder 27.

The connections between the rings 25, contacts 23 and 24 and the line 10—11 are represented on a small scale in Fig. 1, and on a large scale in Fig. 2. The contacts 23 are connected to the transmission line on the side 10 and the contacts 24 are connected to the transmission line on the side 11.

The conducting rings 25 and the contacts 23 and 24 are located within the hollow cylinder 27, on its inner surface, and four movable brushes 22 rotate about the axis of the cylinder and wipe over the contacts 23 and 24. These brushes 22 are respectively connected, as shown, to the four rings provided on the collector 19, which is mounted on the same axis as the commutating cylinder 27, and the terminals of the line amplifier 12 are connected to brushes 20 and 21 wiping over the collector rings.

The line amplifier 12 is thus connected, during the rotation of the brushes 22 of the commutator, to transmit alternately in each direction of transmission.

The cylinder 27 can be displaced longitudinally, in either direction along its axis, so that in the displacement represented by a

downward movement in the drawing, the rings 1, 2, 4 and 5 are brought into contact with their corresponding brushes 22, and in the corresponding upward movement the rings 2, 3, 5 and 6 are brought into contact with the brushes.

The displacements of the cylinder 27 are effected by the controlling devices 26 which are themselves operated by the detector-amplifiers 14 and 15, according to the direction of transmission over line 10, 11.

At the arrival of a signal, coming for instance from the side 10 of the transmission line, the controlling device 26 associated with and operated by the detector-amplifier 14 causes the cylinder 27 to be displaced so as to bring the rings 1, 2, 4 and 5 opposite their corresponding brushes. During the whole of the transmission, the side 10 is thus connected to the input terminals of the line amplifier 12 and the side 11 to its output terminals. The detector-amplifier 15 is put out of action by operation of the corresponding electromagnet 17 by signals received in the detector-amplifier 14 from the line 10. At the end of the transmission, the commutating cylinder 27 is returned to its original position and the amplifier 12 is again connected to transmit alternately in the two directions.

For a transmission in the opposite direction, from 11 towards 10, the commutating cylinder 27 is displaced in the opposite direction to that above and the detector-amplifier 14 is put out of action by operation of the corresponding electromagnet 16.

In the above description and the corresponding drawing, it is supposed that a single group only of contacts 23—24 is provided for each commutator brush 22, but it is obvious that a greater number of contacts may be used, if necessary, in order to work in each case under the best conditions possible for the starting of a transmission in either of the directions of communication.

This increase in the number of contacts 23, 24 will thus increase the frequency with which the alternations are carried out for the same speed of revolution of the brushes 22. The contacts 23, 24 will be connected permanently to the rings 1—6, as indicated in Fig. 2 and in the simplest possible construction the contacts will consist of rings extending over a semi-circle mounted on the drum 27. In the case of a plurality of contacts, they will be connected to the appropriate ring alternately. The number of contacts employed will obviously depend to a certain extent upon the frequency of alternations desired, which frequency must be high enough to permit of the current transmission of a vocal emission or signal element. This frequency, a suitable value of which is found to be 500 per second, is selected in order that the interruption at the commencement of any transmission due to the persistence of a

the alternations may take place sufficiently rapidly that the transmission is not suppressed and lost.

Also, the above described arrangement operates as well without synchronism between the different commutators placed on the line as with synchronism. In the latter case, however, it is necessary to take into account the time of propagation of a signal on the line. The synchronism, if desired, can be obtained by any known means, such as by employing synchronous motors at 18 and it is also advantageous to obtain the synchronism between all the amplifiers of the same station, as the sending of a synchronizing current can then be effected under the control of a single station.

It is to be understood that the above described arrangement providing rotating commutators has only been cited by way of example and that the invention is not limited thereto. Other devices may be used for the reversal of the amplifiers according to the invention, such as polarized or non-polarized electromagnets and further, instead of commutators, two-way amplifiers can even be used which transmit in either direction of communication and one of the directions of transmission of which would be alternately made inactive by electrical or mechanical means.

In a general manner it is to be understood that the scope of the invention is only limited by that of the appended claims and of the prior art.

I claim:

1. Method of telecommunication over a single circuit common to both directions of communication, which comprises continuously reversing the direction of transmission of the amplifying or repeating means along the line, at predetermined intervals of time, during non-transmitting periods, and setting the said amplifying means to transmit in the direction of the communication only, at a communication.

2. Method of telecommunication over a single circuit common to both directions of communication, which comprises continuously reversing the direction of transmission of the amplifying or repeating means along the line, at predetermined intervals of time, during non-transmitting periods, the said reversals following one another with a frequency high enough to permit of the correct transmission of a signal element, and setting the said amplifying means to transmit in the direction of the communication only, at a communication.

3. Method of telecommunication over a single circuit common to both directions of communication, which comprises continuously reversing the direction of transmission of the amplifying or repeating means along the line, at predetermined intervals of time, dur-

ing non-transmitting periods, and setting the said amplifying means at the beginning of and for the duration of each transmission, to transmit only in the direction corresponding to the communication.

4. Method of telecommunication over a single circuit common to both directions of communication, as claimed in claim 1, wherein all the amplifying means along the line are controlled in synchronism.

5. Method of telecommunication over a single circuit common to both directions of communication, which comprises continuously reversing the direction of transmission of the amplifying or repeating means along the line, at predetermined intervals of time, during non-transmitting periods, and setting the said amplifying or repeating means, at a communication and for the duration thereof, to transmit only in the corresponding direction, the reversals continuing for a certain interval of time at the beginning of each communication.

6. A telecommunication system comprising the combination of a transmission line common to both directions of transmission, amplifying or repeating means in said line for communication currents in the two directions of communication, means for continuously reversing the direction of transmission of said amplifying or repeating means, at predetermined intervals of time, during non-transmitting periods, and means for setting said amplifying or repeating means, at a communication and for the duration thereof, to transmit only in the direction of said communication.

7. A telecommunication system operating over a single circuit comprising transmitting and receiving devices, amplifying means, and a commutating device corresponding to each of said amplifying means, said commutating device comprising a member carrying contacts connected to the telecommunication line and cooperating with brushes connected to said amplifying means, said contacts being so arranged that said amplifying means are connected for transmission alternately in each direction of communication, at predetermined intervals of time, and further conducting means adapted to be brought alone into contact with said brushes, whereby said amplifying means may be set to transmit only in the direction corresponding to the direction of transmission.

8. A telecommunication system operating over a single circuit comprising transmitting and receiving devices, amplifying means, a commutating device corresponding to each of said amplifying means, said commutating device comprising a member carrying contacts connected to the telecommunication line and co-operating with brushes connected to said amplifying means, the said contacts being so arranged that said amplifying means are

connected for transmission alternately in each direction of communication, at predetermined intervals of time, and further conducting means adapted to be brought alone into contact with said brushes, whereby said amplifying means may be set to transmit only in the direction corresponding to the direction of transmission, and means operated by a detector-amplifier connected to said line for displacing said commutator member and thereby bring said conducting means and said brushes into contact.

9. A telecommunication system as claimed in claim 8, wherein a detector-amplifier is connected in each side of the line relatively to the line-amplifying means and operation of one detector-amplifier renders inoperative the other.

10. A telecommunication system operating over a single circuit comprising transmitting and receiving devices, amplifying means, a commutating device corresponding to each of said amplifying means, said commutating device comprising a cylinder carrying, on its inner surface, contacts connected to the telecommunication line and cooperating with brushes connected to said amplifying means and conducting rings adapted to cooperate with said brushes upon longitudinal displacement of said cylinder, whereby said amplifying means is normally connected to said line to transmit regularly and alternately in each direction of communication, at predetermined intervals of time, and is set, at the beginning of and for the period of each transmission, to transmit only in the direction corresponding to the communication, and means operated by a communication cur-

rent from one of the stations for displacing said commutator cylinder in the direction corresponding to that of the communication, to bring said conducting means and said brushes into contact.

11. A telecommunication system operating over a single circuit comprising transmitting and receiving devices, amplifying means, a commutating device corresponding to each of said amplifying means, said commutating device comprising a cylinder carrying, on its inner surface, contacts connected to the telecommunication line and cooperating with brushes connected to a collector and therethrough to said amplifying means and conducting means adapted to cooperate with said brushes upon longitudinal displacement of said cylinder, whereby said amplifying means is normally connected to said line to transmit regularly and alternately in each direction of communication, at predetermined intervals of time, and is set, at the beginning of and for the period of each transmission, to transmit only in the direction corresponding to the communication, detector-amplifiers cooperating with electromagnets connected in each side of the line relatively to the line-amplifying means, and means for displacing said commutator cylinder in the direction corresponding to the direction of the communication, said means being operated by one of said detector-amplifiers and the operation of said detector-amplifier rendering inoperative that connected in the other side of the line.

In testimony whereof I have hereunto affixed my signature.
